PROCESS FOR MAKING GRIDS

Fred Warner, Lendon L. Calhoun, and James E. Herbe, Cincinnati, Ohio, assignors to Avco Manufacturing Corporation, Cincinnati, Ohio, a corporation of Delaware

Application November 16, 1953, Serial No. 392,208

1 Claim. (Cl. 140—71.5)

This invention relates generally to a process for winding grid elements for electron tubes and, more specifically, to a grid winding process and structure suitable for use in fabricating a color selecting shadow masking grid for a cathode-ray tube of the type having a multi-colored phosphor screen.

The wire grid or grids in a conventional electron receiving tube of the triode, tetrode or pentode type are wound on a variety of commercial machines which have been developed solely for fabricating such grids. However, in the cathode-ray tube art the conventional grids, as far as black and white tubes are concerned, are not made of wire. Instead, they comprise a portion of the electron gun and take the form of apertured cup-like or tubular elements.

With the advent of cathode-ray tubes suitable for reproducing images in color, various structures have been suggested which require wire type color selecting or shadow masking grids to be positioned adjacent the phosphor screen. At present few, if any, such tubes are being produced in commercial quantities, and the grid winding structures or machines suitable for fabricating grids of the required type can be found only in the laboratory. Since it is now obvious that cathode-ray tubes of the color type will soon be produced in commercial quantities in order to satisfy the growing demand of the public for color television receivers, it would be desirable to provide a grid winding structure and process suitable for producing color grids in large quantities.

Thus, it becomes an object of this invention to provide a relatively simple grid winding process suitable for winding large grids in commercial quantities.

Briefly, the invention comprises a process for feeding grid wire on to a mandrel which is threaded to space the received wire at the desired grid pitch, i. e., either a uniform pitch or a non-uniform pitch. Means are also provided for fixedly attaching the grid wires to mounting strips and for cutting the finished grid element from the mandrel.

For a better understanding of the present invention, together with other and further objects, advantages and capabilities thereof, reference is made to the following disclosure and appended claim in connection with the accompanying drawings, in which:

Fig. 1 illustrates the complete grid winding structure; and

Fig. 2 illustrates the winding mandrel, in broken view, partially filled with grid wire; and

Fig. 3 illustrates a sectional view of mandrel threads holding the grid wire; and

Fig. 4 illustrates how a seam welder may be used to weld the grid wire to the grid mounting strips; and

Fig. 5 and Fig. 6 illustrate the grid after being removed from the mandrel; and

Fig. 7 illustrates the method used to cut the grid from the mandrel.

Fig. 1 shows a simple form of the invention comprising

2

a winding mandrel 11, preferably tubular in form, which is driven by a conical drive means 12 from either shaft 13 or 16 with the other cone and shaft acting as a dead center. As can be seen from the schematic thread designation shown on mandrel 11 in Fig. 1, the winding mandrel is threaded at a selected pitch. Selection of this pitch is governed by the spacing desired between grid wires in the finished grid element.

For example, if the grid wires are to be evenly spaced, then mandrel 11 should be provided with threads having a uniform pitch, with thread groove spacing equal to the desired grid wire spacing. If, on the other hand, the finished grid element is to have non-uniform wire spacing, then it is necessary that the winding mandrel thread pitch be non-uniform in the desired manner. In other words, if the spacing between grid wires near the top and bottom of the grid element is to be greater than the spacing between the grid wires near and at the center of the grid element, it follows that the thread pitch of the end portions of winding mandrel 11 should be greater than the thread pitch near the center of the mandrel.

Feed screw 14 is made to rotate at the same speed as the winding mandrel 11 in order to drive the engaged support 15, shown diagrammatically in Fig. 1 in block form, along the longitudinal axis of the winding mandrel 11. Wire guide 17, which may be tubular in shape, as shown in Fig. 1, or which may take any other shape suitable for guiding wire 18 into the thread grooves on winding mandrel 11, is fixedly attached to wire guide support 15.

As can best be seen in Fig. 1, wire guide 17 progresses along the longitudinal axis of winding mandrel 11 so as to lay the grid wire 18 in the bottom of the thread grooves of mandrel 11, making it necessary that the driving feed screw 14 have exactly the same pitch as the threads on winding mandrel 11. For example, if the thread pitch on winding mandrel 11 is uniform, then the thread pitch on feed screw 14 must also be uniform. Likewise, in the case where the thread pitch on winding mandrel 11 is non-uniform, the thread pitch on feed screw 14 must be non-uniform in identical manner.

Preferably, wire guide 17 should carry the wire in close proximity to the grooved surface on winding mandrel 11 so that maximum advantage can be obtained from the use of threaded feed screw, and the wire fed into the mandrel grooves with approximately the correct spacing. Final accuracy is obtained by virtue of the spacing between thread grooves on the mandrel surface. If the grooves are accurately spaced, then the grid wires resting in the bottom of the thread grooves will be positioned with equal accuracy.

A wire tensioning device, not shown, may be provided either in wire guide 17, on the wire spool, or between the wire spool and wire guide 17. As best shown in Fig. 2, pegs 19 are provided on the mandrel to function as binding posts for connecting the starting end of the grid wire and for tying off the final end of the grid wire after all the mandrel grooves are filled. As best shown in Fig. 2 and Fig. 4 showing the side of the mandrel not seen in Fig. 1, the mandrel is also provided with positioning pegs 20 which are spaced to receive grid end strips 22. These strips 22 actually comprise a portion of the finished grid frame to which each grid wire is fixedly attached, either by welding, pressure, or some similar fastening means. As can best be seen in Figs. 4, 6 and 7, there are four such end strips required for each grid assembly.

The first pair of grid units strips 22 are placed on positioning pegs 20 before the grid element is wound. As shown in Fig. 4, mandrel 11 is formed to provide a groove or channel on its surface having a longitudinal

axis parallel to the longitudinal axis of the mandrel. Thus, the two end strips 22, when placed on the mandrel, tend to fill in the channeled portion of the mandrel, making a relatively continuous surface over which the grid wires are fed.

The slight curvature of the strips 22 in Fig. 4 arises from the fact that the pressure of the wire as it is placed on the mandrel is sufficient to bend the strips to conform to the curvature of the mandrel surface. As can be seen from Figs. 5 and 6, end strips 22 return to a flat condition after being removed from the mandrel.

In operation, after a pair of end strip elements 22 are placed in position on the positioning pegs 20, the grid wire 18 is fed through wire guide 17 and attached to the starting end peg 19, as shown in Fig. 2, and the mandrel is rotated by drive cone 12 to feed the wire 18 into the mandrel thread grooves. Since lead screw 14 has the same thread pitch as mandrel 11, wire guide 17 is moved by lead screw 14 at the correct speed for positioning the mandrel end of the wire guide directly over the next mandrel groove into which wire 18 is to be fed. When the mandrel is completely filled with wire, the wire is attached to the remaining binding or tie-off peg 19 under tension, and then cut between the wire guide 17 and the tie-off binding peg. At this point the two end strips 22 are held tightly in place in the longitudinal mandrel groove, due to the pressure of the grid wire.

After the mandrel is removed from the driving cones 12, a second pair of end strips are placed directly over the first pair, on positioning pegs 20. As a result, the grid wires are sandwiched between two sets of matching end strips. The assembly is then run through a seam welder, as shown in Fig. 4, where roller 30 acts as the ground or common electrode and rollers 31 and 32 the hot electrodes. Metal inlay 34 may comprise any suitable electrode material, such as Mallory, Tipaloy, etc.

After the unit is taken from the welder, the only operation that remains is to cut the grid from the mandrel. There are many ways in which this cutting operation might be accomplished. One method is shown in Fig. 7, for example, where it can be seen that two slots are formed in mandrel 11 to receive the end strips 22, and the surface between these two slots is formed to provide a cutting edge. After the mandrel is removed from the welder, a simple cutting blade 37, as shown in Fig. 7, can be run across the wires directly above the cutting edge, and the wires severed, as shown. If desired, cutting edges may be provided which remove all wire extending between the two pairs of end strips. In the absence of such a device, grid wires 18 should be trimmed, as shown in Fig. 5 and Fig. 6, so as not to extend beyond the end strip 22.

After the wire is cut between the grid end pieces, the grid may be removed from the mandrel. Preferably, this should be done in such manner as to keep the grid

wires under tension at all times so that the wires do not become either entangled with each other or knot and break.

The grid element which results from each winding operation, as shown in Fig. 5, may be used in any desired tube where it is permissible to operate all grid wires at a common potential. All grid wires are welded or attached to the metal end strips, and thus are at a common potential. Thus, in color tubes of the type using a plurality of interleaved grid elements, co-planar or otherwise, where portions of the complete grid are operated at a potential different from the potential of the remainder of the grid, it will be necessary to use two or more of the grid elements, as the case may be, of the type shown in Fig. 5 and Fig. 6.

Of course, if end strips having the properties of an insulator, i. e., having high dielectric constant, are used, then it is possible to electrically interconnect the various grid wires as desired, and to make adjacent wires operate at different potentials.

Having thus described our invention, we claim:

A process of winding electron tube grid structures comprising the step of placing a pair of end strips in parallel spaced relationship on the surface of longitudinal grooves provided in a tubular threaded winding mandrel, winding grid wire on to said mandrel by spacing each turn to fall into the thread groove, welding said end strips to the grid wire wherever said end strips cross said grid wires by passing one welding electrode along the longitudinal axes of the end strips above the mandrel and by passing the other welding electrode along the longitudinal axes of the end strips inside the mandrel, cutting the grid wire which extends across said longitudinal mandrel groove between end strips, and removing the grid wire and fastened end strips from the mandrel while keeping the wire under tension.
